Their Attorney,

UNITED STATES PATENT OFFICE.

WALTER H. HART AND DAVID GOULD, OF NEW BRITAIN, CONNECTICUT, ASSIGNORS TO THE STANLEY WORKS, OF NEW BRITAIN, CONNECTICUT, A CORPORATION OF CONNECTICUT.

FOLDING RULE.

Application filed September 12, 1921. Serial No. 500,161.

To all whom it may concern:

Be it known that we, WALTER H. HART and DAVID GOULD, citizens of the United States, and residents of New Britain, county 5 of Hartford, State of Connecticut, have invented certain new and useful Improvements in Folding Rules, of which the following is a specification.

This invention relates to folding rules 10 made up of rule sections formed of thin strips of resilient metal and pivoted together at their overlapping ends.

The object of the present invention is to provide a rule of this kind having features 15 of novelty and advantage, and more particularly to provide an improved arrangement wherein the metal sections may yield to permit the sections to be turned relatively to one another, and these sections are firmly 20 maintained in proper relation.

In the accompanying drawings, wherein I have shown for illustrative purposes one embodiment which the present invention may take,

25 Fig. 1 is a view showing two sections of the rule in extended relation.

Fig. 2 is a top plan view of the lower section of Fig. 1.

Fig. 3 is a view taken longitudinally and 30 centrally, through the joint between the sections of Fig. 1.

Figs. 4, 5 and 6 are sectional views respectively taken on lines 4—4, 5—5 and 6—6 of Fig. 1.

35 Referring to the drawings in detail, *a*, *a'* etc. denote the rule sections each comprising a relatively thin strip of resilient metal, and *b*, is a rivet pivotally connecting together the overlapping ends of the contiguous sections.

In the present illustrative disclosure, each section is provided along its longitudinal center, with a stiffening corrugation 11 and these corrugations terminate in a pair of 45 branches or corrugations 12, 12, between which a rivet *b* is positioned. The portions of the sections adjacent the rivets are bent up out of the plane of the sections and flush with the tops of the corrugations 12, thereby 50 providing bosses 14, 14. It will be seen that the corrugations 12 of contiguous sections are so arranged that those of one section, in the present instance the lower section *a'*, are

adapted to nest in the grooves provided by the corrugations of a contiguous section, 55 when these sections are in either folded up or in extended relation, and thus the sections are maintained against relative turning movement.

If desired the overlapping end of one 60 section may be provided with holes or recesses 15 and the contiguous section with round protuberances 16 arranged to engage in the holes when the sections are in alignment. These holes and protuberances 65 provide additional means for maintaining the parts against relative turning movements and also serve to prevent the parts from moving endwise or longitudinally of each other in the event wear on the stems of the 70 rivets becomes excessive or the edges of the perforations in the sections through which the rivets pass become enlarged.

It will be seen that the rivets so connect contiguous sections together that when these 75 sections are turned relative to one another the metal of the sections must yield to permit the corrugations to ride into and out of nesting relation.

In accordance with the present invention, 80 provision is made for rendering the portions of the sections adjacent the rivets more flexible so that the sections may be easily turned and excessive strains on the pivotal connections may be reduced or eliminated. 85 To this end, in the present illustrative disclosure, one of the overlapping ends of the contiguous sections is slotted or slotted as at 20 to both sides of the pivot *b* thus providing a spring 21 through which the rivet extends. 90 It will be seen that with this arrangement, upon turning contiguous sections relative to one another, the spring 21 will flex permitting the corrugations to ride into and out of nesting relation, as the case may be. 95

It is to be clearly understood that the present disclosure of the invention is by way of illustration only and it is not to be taken as restrictive of my conception, for the invention is susceptible of various modifications and changes; for instance, both or either of the overlapping ends of contiguous sections may be slotted, slotted, or otherwise weakened in the areas adjacent the pivotal connections so as to increase the flexibility of 100 105 these portions or areas; also the stiffening

and interlocking corrugations and the slits or slots may have various forms and arrangements.

We claim as our invention:—

- 5 1. In an all-metal folding rule, rule sections each comprising a thin strip of resilient metal, one of said sections having an integral spring formed therein, both ends of said spring being connected with its section, 10 and a pivotal connection between said spring and the overlapping end of a contiguous section.
- 15 2. In an all-metal folding rule, rule sections of thin resilient metal having interengaging means for maintaining the sections in alinement, and a pivotal connection between the overlapping ends thereof, one of said sections being slotted on opposite sides of said connection by separated slots, thus 20 forming a spring, both ends of which are connected with the section.
- 25 3. In an all-metal folding rule, rule sections of thin resilient metal having at their overlapping ends corrugations adapted to nest, and a rivet connecting said sections, one of said sections being slotted on opposite sides of said rivet by separated slots, thus forming a spring, both ends of which are connected with the section.
- 30 4. In an all-metal folding rule, rule sections each comprising a thin strip of resilient metal, the overlapping ends of contiguous sections having bosses adapted to seat one in the other, and a rivet extending through 35 apertures in said bosses, one of said bosses being slotted to both sides of said rivet.
- 40 5. In an all-metal folding rule, rule sections, and means for pivotally connecting the overlapping ends thereof, each of said sections comprising a thin resilient strip of metal provided with a longitudinally extending stiffening corrugation terminating at the overlapping ends of the sections in a pair of corrugations equally spaced on opposite sides of said pivotal connection.
- 45 6. In an all-metal folding rule, rule sec-
- tions jointed together, each section comprising a thin strip of resilient metal having a stiffening corrugation extending substantially throughout its length, the corrugations of contiguous sections being arranged to nest when the sections are in alinement, the overlapping ends of contiguous sections also having interengaging holes and protuberances for maintaining said sections in proper relation. 55
7. In an all-metal folding rule, rule sections, each comprising a thin strip of resilient metal, and each section having a corrugation extending throughout its length and 60 transverse shoulders that are adapted to nest together to maintain proper relation of the sections longitudinally.
8. In an all-metal folding rule, rule sections, each comprising a thin strip of metal, 65 pivots connecting said sections, and each section having a corrugation extending from one pivot to the opposite end of the section and transverse shoulders that are adapted to nest together to maintain proper relation 70 of the sections longitudinally.
9. In an all-metal folding rule, pivoted rule sections, each comprising a thin strip of resilient metal, and each section having a corrugation extending throughout its entire 75 length, said sections having transverse shoulders formed therein in symmetrical pairs on opposite sides of said pivot for preventing longitudinal movement of said sections relative to each other. 80
10. In an all-metal folding rule, rule sections, each comprising a thin strip of metal, pivots connecting said sections, and each section having a corrugation extending from one pivot to the opposite end of the section, 85 said sections having transverse shoulders formed therein in symmetrical pairs on opposite sides of said pivots for preventing longitudinal movement of said sections relative to each other.
